UNITED STATES PATENT OFFICE.

ANDREW J. FLOWERS AND MALON I. FLOWERS, OF SPRINGFIELD, MISSOURI.

MOTOR.

SPECIFICATION forming part of Letters Patent No. 349,638, dated September 21, 1886.

Application filed January 5, 1886. Renewed August 28, 1886. Serial No. 212,097. (No model.)

To all whom it may concern:

Be it known that we, ANDREW J. FLOWERS and MALON I. FLOWERS, citizens of the United States, residing at Springfield, in the county of Greene and State of Missouri, have invented 5 certain new and useful Improvements in Motors, of which the following is a specification, reference being had therein to the accompanying drawings.

Our invention relates to rotary engines, and our object is while running an eccentric cylinder in a cylindrical case to form guides for the pistons which work in the eccentric cylinder, in order to give them a more steady and uniform movement, as will be hereinafter more fully set forth.

In the accompanying drawings, making part of this specification, Figure 1 represents a vertical section taken crosswise of the driving-shaft. Fig. 2 is also a vertical section, but taken in line with the shaft. Fig. 3 represents a plan view of the guide-ring and bottom view of the pistons.

In the figures, A represents the case of the machine, having a cylindrical internal bore. B B' represent the heads of this case, which are bolted in place in any suitable manner. C and D represent the inlet and outlet pipes of this case. In the head B' is a circular recess, which 25 is concentric with the bore of the case. In this recess is placed an annular ring, G, the outer face of which is flush with the internal surface 30 of the head B'.

E represents a skeleton cylinder having a 35 drying-shaft, F, passing through it. The diameter of the cylinder E is less than that of the bore of the case, thereby permitting said cylinder to be placed eccentrically within said case. The shaft F has bearings in both of the 40 heads. The cylinder E is so located in the case that its periphery will touch the internal surface of the case at a point between the inlet and outlet pipes, as represented in Fig. 1. Cut

from near the center of the cylinder E to its periphery are rectangular grooves or openings 45 in which are placed the pistons H H. The outer edges of these pistons are rounded, the pistons being solid metal. The ring G is provided with two curved slots, a a. A pin or pins, i i, pass through the slots a a and into 50 one end of the pistons. When the motor is in operation the ring G revolves, and the pins i i, playing in the slots a a, cause the pistons to move outward. The pistons are caused to move inward by the contact of the interior surface of the case with the outer edges of said pistons. The pistons start to move outward when the periphery of the cylinder begins to have contact with the internal surface of the case. Steam is thus taken in at one port, and, 55 pressing upon the piston, causes the cylinder to revolve, the steam escaping at the next or exit port, the piston after it passes it being forced entirely within its recess, and thus the pistons are alternately moved outward and inward, so long as steam is admitted. This motor 60 may be used for steam or gas or water, as may be desired, or may be used as a pump, submerged or suction.

Having thus fully described our invention, 70 what we claim as new, and desire to secure by Letters Patent, is—

The combination of the case A, with its inlet and outlet ports, the eccentrically placed cylinder therein, the pistons H H of said cylinder, and the slotted concentric ring G, embedded in the head of the case, substantially 75 as and for the purpose specified.

In testimony whereof we affix our signatures in presence of two witnesses.

ANDREW J. FLOWERS.
MALON I. FLOWERS.
